UNITED STATES PATENT OFFICE.

WILLIAM P. KRAUSE, OF CHICAGO, ILLINOIS, ASSIGNOR TO MUMFORD MOLDING MACHINE COMPANY, A CORPORATION OF NEW JERSEY.

MOLDING-MACHINE.

1,340,658.

Specification of Letters Patent.

Patented May 18, 1920.

Application filed February 10, 1919. Serial No. 275,937.

To all whom it may concern:

Be it known that I, WILLIAM P. KRAUSE, a citizen of the United States, residing at Chicago, in the county of Cook and State of Illinois, have invented certain new and useful Improvements in Molding-Machines, of which the following is a specification.

This invention relates to improvements in molding machines, especially to that class of machines in which a squeeze head carrying yoke is used.

The object of the invention is to provide a molding machine with the upper front part of the base so constructed that the table-carrying portion, together with the table, overhangs, so that the molder operating the machine may stand close to the front of the table, provision being thus made for his feet. This enables him to get a direct lift or move the flask straight up without bending unduly at the conclusion of the molding operation, and, in case of the machine utilizing actuating valves, or the like, the operator is enabled to operate said valves more readily.

Another object of the invention consists in extending the rear of the base portion rearwardly of the table-carrying structure and table, so that the greater portion of the base lies to the rear of the axis of rotation of the yoke. By this construction, as will be readily seen by reference to the drawings, more support is provided for the yoke and squeeze head when the yoke is thrown into an inoperative position. In other words, the tendency of the machine to tilt or rock, due to the location of the center of gravity of the yoke and allied mechanism falling to the rear of the center of the table when thrown into inoperative position, is counteracted.

These and other objects of the invention will be more fully set forth and described in the following specification, taken in connection with the accompanying drawings, in which—

Figure 1 is a side elevation of an embodiment of my invention;

Fig. 2 is a vertical transverse section, taken through the body of the machine, a portion of the cylinder being shown in elevation and other portions broken away; and

Fig. 3 is a plan view of the base portion of the machine.

Like numerals refer to like elements

throughout the drawings, in which 10 designates generally the base portion of the machine. This base portion is provided with a central aperture or chamber 10^a and with bearing members 10^b. The base portion 60 rests upon the bottom surface 10^c, the rear portion thereof being semi-circular in contour and inclined rearwardly from top to bottom, as clearly shown in Figs. 1 and 3, for example. The bearing members 10^b are 65 located closer to the front of the base portion than to the rear, whereby the major portion of the base 10 lies to the rear of the bearing members, as shown in Figs. 1 and 3, for a purpose to be hereinafter described. 70 The upper portion of the base projects forwardly, as shown in Fig. 1, so that in effect the top of the base is offset forwardly with respect to the bottom.

Seated in the chamber 10^a is the cylinder 75 11, flanged intermediate its top and bottom, as indicated by numeral 11^a, this flange resting on the top of the base and being secured thereto by bolts 12. In the embodiment shown the cylinder is provided with a piston 80 13 centrally apertured to reciprocate upon a fixed trunk or post 14^a integral with the circular plate 14, which closely fits the interior of the cylinder, and is secured to the bottom thereof by means of screws 16. The 85 reciprocable piston 13 carries the usual table 15, on which is supported the flask—not shown—when molding operations are taking place.

The yoke 17 is secured to a pivotal shaft 90 18, in any suitable manner, at the lower extremities of the yoke arms, and carries a cross-bar 19 extending across and between such yoke arms. This cross bar carries a squeezer head 20, against which the flask and 95 its sand content may be squeezed by lifting the table 15. When no squeezing operation is contemplated, and during the filling of the flask, the yoke and squeezer head are moved to what I term inoperative position, 100 as indicated in dotted lines in Fig. 1. It will be observed that when in this position considerable displacement of weight from the center of gravity of the machine, as ordinarily constructed, occurs, normally 105 tending to cause tilting or locking of the machine. In my construction, however, the peculiar construction of the base member 10 serves to counteract this tilting motion, by relatively constructing and arranging the 110

yoke bearings and bottom of the base so that the greater portion of the latter lies to the rear of the bearings 10^b.

Inasmuch as the table projects upwardly 5 vertically from the top of the base 10, it will be seen that the table is offset forwardly with respect to the bottom thereof, so that the operator of the machine, when standing at the front thereof in the molding operation, may be practically in contact with 10 the front of the table, due to the cutting away and recession of the front of the base, which enables him to place his feet beneath the machine, so that his body is in substantial 15 contact with the front thereof. He is thus enabled to lift the flask directly upwardly when removing the same, without having to bend his body, a convenience which will be greatly appreciated by those skilled 20 in this art. As stated in the preamble also, where knee-actuated operating valves are provided at the front of the machine, their actuation is rendered easier by the proximity of the operator to the front of 25 the machine.

Another advantage of my construction lies in the fact that I may provide for location of the table surface at practically any desired height by locating the supporting 30 flange 11^a at a position necessary to locate properly the table surface, and different cylinders with the supporting flange at any desired location may be provided and readily substituted in this construction without 35 requiring the substitution of the entire machine.

It will also be apparent that my invention

is susceptible of many modifications and improvements, and I do not wish to be restricted to the form shown or described beyond the scope of the appended claims. 40

What I claim is:

1. In a device of the class described, a base member, and a cylinder member, said cylinder member being secured to the upper 45 portion of said base and supported thereby, the axis of said base member being inclined rearwardly from top to bottom.

2. In a device of the class described, a base member, a cylinder member, said 50 cylinder member being secured to the upper portion of said base and supported thereby, the axis of said base member being inclined rearwardly from top to bottom, and a yoke member pivotally carried by said base 55 and pivoted about an axis adjacent the front thereof.

3. In a device of the class described, a tubular base, and a cylinder supported thereby adjacent the top thereof, the axis of 60 said base being inclined rearwardly from top to bottom.

4. In a device of the class described, a tubular base, and a cylinder supported thereby adjacent the top thereof, the axis of 65 said base being inclined rearwardly from top to bottom, said base being provided with a chamber or recess in the upper portion thereof, said cylinder having its bottom portion depending into said chamber. 70

In testimony whereof, I have subscribed my name.

WILLIAM P. KRAUSE.
